UNITED STATES PATENT OFFICE.

WILLIAM P. HAMMOND, OF NAPA, CALIFORNIA.

ORE-CRUSHER.

SPECIFICATION forming part of Letters Patent No. 267,687, dated November 21, 1882.

Application filed July 25, 1882. (No model.)

To all whom it may concern:

Be it known that I, WILLIAM POTTER HAMMOND, a citizen of the United States, residing at Napa, in the county of Napa and State of California, have invented a certain new and useful Improvement in Ore-Crushers, of which the following is a specification.

My present invention relates to an improvement in that class of ore-crushers for which Letters Patent of the United States were granted to me December 24, 1872, No. 134,201; and the object of my invention is to impart to the stamper a greater whirling or rotating effect after the end of the cam has left the tappet, and thereby grind or crush the ore between the face of the stamp and the battery-plate before the impetus given to the stamp is lost. I accomplish this object by the means illustrated in the accompanying drawings, in which—

Figure 1 is a front elevation of my improved device. Fig. 2 is a vertical section of the same, taken in the planes indicated by line xx of Fig. 1. Fig. 3 is a perspective view of the cam. Fig. 4 is an under view of beveled tappet and cam.

The same letters refer to the same parts throughout the several views.

It is a well-known fact among mill men who reduce ores by means of the well-known stamp-mill, in which the stamper-shaft is lifted, partly rotated, and dropped by means of a revolving cam and a tappet on the stamper-shaft that the more nearly the stamper is caused to perform a complete rotation after the end of the cam leaves the tappet and the face of the stamp falls upon the ore upon the battery-plate the greater is the crushing and grinding effect produced, and that the ore is thus reduced much more rapidly than where the stamp falls "dead"—that is, when but little or no rotation is produced. In order to accomplish this result I construct the outer edge, A, of the lower face of my tappet B with a continuous bevel, as shown. The cam C is also beveled outwardly from heel to toe at an angle to correspond with the beveled edge around the face of the tappet, so that when power is applied to the cam through the medium of the cam-shaft D and pulley D', the beveled edge

of the cam will move along the corresponding beveled edge of the tappet from heel to toe, and impart to the stamper a rotary motion that will continue after the point or toe of the cam has left the tappet, and thereby produce the desired result.

In my former invention, above alluded to, I made the face of the tappet concave, but the vortex of such concavity was so great that only a partial result was accomplished as the face of the cam operated along the sides of the vortex of the tappet, thereby causing more friction and less "throw" or circular impetus after the cam had left the tappet, while in my present improvement the cam travels around upon the edge of the tappet with the results above stated.

It will be seen that by reason of the beveled edge of the tappet and the action thereon of the beveled cam, the lifting and turning movement of the tappet is continued after the outer edge of the cam has left the tappet and until the cam has entirely let go of it, which is just at the point where the cam imparts to the tappet its most effective rotary impulse.

Having thus described my invention, what I claim, and desire to secure by Letters Patent, is—

In an ore-crusher or stamp-mill, the combination, with the stamp-stem, of a tappet, B, secured thereon and provided with a beveled or inclined edge around its lower face, and a beveled cam, C, secured to the cam-shaft D, and adapted to engage with the beveled edge of the tappet, whereby the conjoint action of the cam and tappet will impart a lifting and turning movement to the stamp-stem, which movement is continued after the outer edge of the cam has left the tappet and until they are entirely disengaged, substantially as shown and described.

In testimony that I claim the foregoing I have hereunto set my hand and seal this 19th day of June, 1882.

WILLIAM P. HAMMOND. [L.S.]
